UNITED STATES PATENT OFFICE.

COLE STICKLE, OF INDIANAPOLIS, INDIANA, ASSIGNOR TO OPEN COIL HEATER & PURIFIER COMPANY, OF INDIANAPOLIS, INDIANA, A CORPORATION.

HEAT-EXCHANGE APPARATUS.

Application filed October 28, 1922. Serial No. 597,594.

This invention relates to a heat exchange or transferring apparatus.

The invention is made particularly for use in connection with a paper or cloth drying machine for utilizing the exhaust steam and condensation water therefrom for heating the air in the rooms containing the machines, but the invention is not limited to such use, as the source of heating fluid or liquid may be other than that mentioned and the medium receiving the heat may be other than air.

The chief object of the invention is to transfer in a unit of time more of the available transferable heat from a heat containing fluid, such as exhaust steam or hot water, than heretofore has been the practice to a surrounding medium such as air or the like.

20 The chief feature of the invention consists in passing a relatively thin layer of the heated liquid, such as hot water, through a flat substantially horizontal conductor which it does not and cannot completely fill and maintaining therein a lower pressure such as a partial vacuum, than that to which the heated liquid has been previously subjected, such as atmospheric or greater pressure, whereby when the medium to be heated is passed around the conductor, it cools the contents, condensing the vapor causing a partial vacuum in the conductor which automatically releases the vapor from the heated fluid to fill the unoccupied portion of the conductor as will be hereafter more fully explained.

Briefly, the invention consists of a series of relatively flat elongated substantially horizontally disposed conductors or chambers connected at their ends to form a continuous sinuous coil through which the heated liquid flows in a thin film and about which in the steam liberating space provided there is produced through multiple evaporation and condensation, a vapor 1700 times that of the liquid from which it was produced, and passing around said conductors air or like means, through suitable drawing or forcing apparatus and subjecting the conductor to a vacuum pump for reducing the pressure therein, whereby heat is more efficiently transferred from the high

temperature condensation to the cold air than could be accomplished with present installations.

55 A construction feature of the invention consists in the sectionalized and battery arrangement of the included parts of the heat exchanger.

The full nature of the invention will be 60 understood from the accompanying drawings and the following description and claims:

In the drawings Fig. 1 is a side elevation of the invention applied to exhaust steam, 65 a portion of the heater casing being broken away to show in section the several sections of tiered heating units. Fig 2 is an end elevation of the simplest form of the invention with the tiered units shown in longitudinal section and connected relation. Fig. 3 is an enlarged diagrammatic view of the same form of the invention, parts being broken away to show the heater in section. Fig. 4 is a top plan view of one of the heating units. Fig. 5 is an end elevation of two of the units in superposed relation. Fig. 6 is a central sectional view of a thermic vacuum trap. Fig. 7 is a top plan view of the heater showing the battery arrangement. Fig. 8 is an end view of the heater with the casing removed showing the end to end battery arrangement.

In Figs. 1, 7 and 8, there is shown the combination of means for causing air to pass over the heating units, thermic vacuum traps and a vacuum pump associated with the heat exchanger units which is adapted to handle exhaust steam. Figs. 2 and 3 illustrate the simplified form of the invention adapted to handle hot water, the thermic vacuum traps being unnecessary. The heat supplying line 17 discharges into the header 18 controlled by valve 19. Vacuum pump 22 controlled by controller 23 is connected by line 21 to discharge line 27 of the header 18'. Line 25 including balanced valve thermic vacuum trap 26 connects the vacuum pump supply line 21 with the header.

190 The heat exchanger includes the casing 43 open at one end to form the air intake 43^a and the other end 43^b is associated with the suction fan having the housing 44 and discharge 45 and operable by motor 46 for

5 drawing air through the casing. A blower may secure the same operation. The air passing through the casing abstracts heat from the heating units and thus is preheated
 10 and may be supplied to rooms or chambers, wherein heated air is required. Specifically, in paper and textile work the heated air is of value since it has greater capacity for moisture than cold or raw air and thus more efficient operation in the aforesaid plants is obtainable.

15 Each section of the exchanger comprises a plurality of superposed substantially horizontally arranged heating units connected in reverse bend arrangement. Each unit comprises a flat elongated tubular element 30 of cast metal and including exteriorly positioned heat radiating fins 31. Upon opposite sides and at opposite ends of each element is a threaded opening 32 which is considerably smaller than the cross sectional area of the element and upon the opposite side therefrom is an abutment 33. When the elements are arranged in superposed or
 25 tiered relation close nipples 34 connect openings 32 and when thus connected abutments 33 separate the elements and provide an air passage therebetween and the spacing by reason of said abutment is such that a very slight pitch is secured in each unit from the median plane therebetween whereby the elements are drained and can never fill with water. The coils are thus secured in reverse bend relation and the contractions correspond with the connections. In the present form of the invention each opening 32 is surrounded by a boss which assures that a portion of the liquid flowing along the bottom of the unit will always be retained in
 35 said unit. The uppermost unit of each section may be provided with an auxiliary connection 37 if desired, as hereinafter described, but the uppermost unit of each section preferably is connected to the supply line 17 as shown in Figs. 2, 3 and 8.

40 Each section is connected by an intake pipe 38 controlled by valve 39 with header 18 and supply line 17. The lowermost unit has the discharge 40 controlled by valve 41 discharging into the thermic vacuum trap 42, which trap is shown in detail in Fig. 6. The essential feature thereof is that it includes a by-pass for maintaining the vacuum and preventing the steam from injuring the pump. A detailed description of the valve is not believed necessary since the same is set forth in Patent No. 1,468,178, dated September 18, 1923. The area of the discharge aperture 40 is at least equal to the area of the inlet 32, and no portion of the passage between the inlet and the outlet has an area less than the area of the inlet.

45 The connection 37 in certain of the uppermost units connects to a live steam supply. The same is provided to permit raw or live

steam to be introduced into the intake or initial heating sections.

Briefly, the operation is as follows: When high temperature condensate is supplied to the heater the initial action is to condense 70 the steam flashed from the hot water thus giving up the latent heat.

When hot water is supplied to the unit the vacuum trap illustrated is omitted if desired. If steam is used a vacuum trap 75 should be employed to protect the vacuum pump. Upon the initial supply of hot water to the section a portion of the water is vaporized and the operation of the fan simultaneously therewith abstracts heat and the vapor condenses causing a partial vacuum. The vacuum pump thereupon maintains this vacuum. The result is that to fill the chamber above the channel a portion of the water flowing through the conductor immediately 80 vaporizes and to do so it takes the necessary heat from the water passing therethrough and forms vapor. The volume of the vapor being much greater than that of the water the exchange of heat is accelerated. As the heat is abstracted from this vapor and also from the water by the air passing over the conductors, the temperature of both and the conductors is simultaneously reduced. This causes the vapor to condense and thus a succession of vaporizations and condensations occur throughout each section until finally the lowermost section discharges cooler water. Since the intake at the top of the section is no greater than the outlet in the bottom of the section, the sections cannot fill unless the temperature gets so low that the water will freeze. To prevent such action the raw steam supply connection previously described is provided and the temperature of the entire unit is maintained sufficiently high to prevent such freezing particularly in the lowermost coils of the exposed sections.

50 The chief feature of the invention, therefore, resides in slowly passing a liquid having a predetermined amount of heat for a given temperature and pressure slowly through a conductor which it cannot fill and at a reduced pressure, whereby there is generated from the liquid a vapor that fills the unoccupied portion of the conductor, and which subsequently recondenses as the temperature falls by reason of continued heat abstraction, whereby cyclic vaporization and condensation is obtained resulting in 100 a higher rate of heat transference than heretofore obtainable in condensers or heaters.

55 The invention claimed is:

60 1. A heat exchange apparatus including an elongated and substantially horizontally disposed conductor having a relatively shallow chamber formed therein and adapted to receive a thin film of heated liquid in the 105 lower part thereof and leaving the upper 110

- part of the chamber for receiving vapor formed from said liquid, means for supplying heated liquid to said conductor, means acting externally for abstracting heat from the chamber for condensing the vapor therein thereby forming a partial vacuum therein, and means for maintaining the partial vacuum for permitting vaporization of the liquid.
- 10 2. A heat exchange apparatus including an elongated conductor, means for supplying heated liquid for partially filling the same and leaving a chamber above the liquid for vapor to be formed therefrom, means acting externally for abstracting heat from the chamber for condensing the vapor therein and thereby forming a partial vacuum therein, means for maintaining the partial vacuum for permitting the vaporization of the liquid, and casing means enclosing said conductor and connected to the externally acting means for abstracting heat.
- 15 3. A heat exchange apparatus including a conductor adapted to receive a thin film of heated liquid only in the bottom thereof, means for supplying heated liquid to one end thereof, an exhaust from the other end of the conductor, and vacuum producing means for maintaining a reduced pressure in said conductor for vaporizing part of the liquid to fill the remainder of the conductor.
- 20 4. A device as defined by claim 3, characterized by the addition of a casing enclosing the conductor, and means for moving air through the casing for rapidly abstracting heat from the conductor.
- 25 5. The combination with means for maintaining a vacuum, and means for continuously supplying a heated vaporizable liquid, of heat exchange apparatus having a casing including an air passage therethrough, and heat transferring means in said casing connected to the liquid supply means at one
- 30 end and to the vacuum means at its opposite end, said heat transferring means comprising a relatively flat elongated tubular element including a lower liquid conducting channel forming portion, and an upper vapor confining chamber forming portion in substantially continuous open communication, said element being arranged to prevent filling with liquid when in operation.
- 35 6. The combination with means for maintaining a vacuum, and means for continuously supplying heated vaporizable liquid, of heat exchange apparatus having a casing including an air passage therethrough, and heat transferring means in said casing having one end communicating with the liquid supply means and its opposite end with the vacuum means, and comprising a plurality of relatively flat elongated tubular elements, each including a lower liquid conducting channel forming portion and an upper vapor confining chamber forming portion in substantially continuous open communication, and outlet and intake means forming contractions at opposite ends of each element, adjacent elements being connected thereby to provide communication between the elements.
- 40 7. A device of the character defined by claim 6, characterized by said elements being arranged in superposed and reversed relation, whereby the connecting contractions form return bends.
- 45 8. A heat exchange apparatus having an air passage therethrough and a branchless heat supplying passage therein, said last mentioned passage having an inlet and an outlet, means for maintaining the latter at a lower pressure than the inlet, said passage including a lower liquid conducting channel forming portion and an upper vapor confining chamber forming portion thereabove, the outlet of the passage being at least as large as the inlet whereby at least as much of the heating medium is discharged through the outlet in a given time as is supplied to the passage through the inlet in the same time.
- 50 9. A device of the character defined by claim 8 characterized by the area of any portion of the heat supplying passage being not less than the area of the inlet.
- 55 10. A device of the character defined by claim 8, characterized by the area of any portion of the passage being not less than the area of the outlet.
- 60 In witness whereof, I have hereunto affixed my signature.
